FIG. 1.

FIG. 2.

UNITED STATES PATENT OFFICE

2,210,801

ANTIGLARE HEADLIGHT

Newton W. Doane, San Francisco, Calif.

Application March 8, 1939, Serial No. 260,631

1 Claim. (Cl. 240—41.1)

This invention relates to improvements in headlights.

The principal object of this invention is to produce a headlight whereby the glare would be eliminated.

A further object is to produce a device of this character which may be employed with the ordinary motor vehicle without altering its construction.

10 A further object is to produce a device of this character which is neat in appearance, economical to manufacture and one which will comply with the ordinary State requirements.

Other objects and advantages will be apparent 15 during the course of the following description.

In the accompanying drawing forming a part of this specification and in which like numerals are employed to designate like parts throughout the same,

20 Fig. 1 is a front elevation of my headlight; and Fig. 2 is a cross sectional view taken on the line 2—2 of Fig. 1.

Automobiles in approaching each other at night often employ headlights which are blinding to 25 the driver of the other car. This blinding of the driver very often causes serious accidents. It is to avoid this difficulty that I have devised my headlight.

In the accompanying drawing wherein for the 30 purpose of illustration is shown a preferred embodiment of my invention, the numeral 5 designates a shell which may be circular in cross section when viewed from the front, or may be the shape shown in Fig. 1, that is the side walls of 35 the front portion of the shell are of greater height than the width of the top and bottom walls thereof, and as shown in Fig. 2 the rear portion 6 has a reflector 7 therein.

The reflector 7 includes upper and lower concaved elements and the upper element is directed 40 rearwardly and downwardly from the top and side walls, while the lower element is reversely curved rearwardly and upwardly from adjacent the bottom and side walls and meets the rear end 45 of the upper element slightly above the bottom wall. The forward portion of the lower reflecting element is curved upwardly and rearwardly and has its upper edge terminating above the juncture of the rear ends of the upper and lower elements, to provide a light well 8 which entirely 50 faces the upper element, as clearly shown in Fig. 2.

Mounted in the well 8 is a light bulb 9 that extends rearwardly at an acute angle to the longitudinal axis of the shell, so that the rays from 55 the bulb will be reflected by the upper element, parallel with the walls of the front portion, as indicated by the dot and dash-lines in Fig. 2.

The interior of the front portion has its surface

11 polished to provide a reflecting surface, and mounted in the front portion is an element 12 that has a nonreflecting upper surface and which may be painted black for that purpose. The element 12 is curved downwardly and forwardly 5 from the upper edge of the well 8 and disposed along the bottom and lower portions of the side walls to the forward end of the shell, which is closed by the usual lens 13.

10 From the above description and disclosure in the drawing, it will be obvious that the rays of illumination from the bulb 9 and well 8 must be reflected before emanating from my headlight, thus eliminating any glare and by providing the element 12 with a non-reflective surface, I eliminate 15 the upward beam which would be otherwise objectionable.

By virtue of the black coated surface, all glare of the headlight, to the approaching motorist, 20 is eliminated.

In other words, as a motorist or pedestrian draws near to my improved light, all danger of a confusing blinding ray is in reality reduced to a minimum.

25 It is to be understood that the form of my invention herewith shown and described is to be taken as a preferred example of the same and that various changes relative to the material, size, shape and arrangement of parts may be resorted to without departing from the spirit of 30 the invention or the scope of the subjoined claim.

Having thus described my invention I claim:

A headlight comprising a shell including a front portion having side walls of a greater height than the width of the top and bottom walls, a 35 reflector in the rear portion of the shell and including upper and lower reflecting concaved elements, said upper element being directed rearwardly and downwardly from said top and side walls, said lower element being reversely curved 40 rearwardly and upwardly from adjacent said bottom and side walls and meeting the rear end of said upper element slightly above the bottom wall, said lower reflecting element having its forward portion curved upwardly and rearwardly 45 and having its upper edge disposed above the juncture of the rear ends of said upper and lower elements to provide a light well entirely facing said upper element, a light bulb in said well and extending rearwardly at an acute angle to the 50 longitudinal axis of the shell, whereby light rays from the bulb will be reflected by the upper element parallel with said walls, and a non-reflecting element curved downwardly and forwardly from the upper edge of the well and disposed 55 along said bottom wall and lower portions of said side walls to the forward end of the shell.

NEWTON W. DOANE.
